F. W. TULLY

COLLAR AND CUFF

Filed Sept. 2, 1921

UNITED STATES PATENT OFFICE.

FRANCIS W. TULLY, OF BROOKLINE, MASSACHUSETTS.

COLLAR AND CUFF.

Application filed September 2, 1921. Serial No. 497,891.

This invention relates to collars and cuffs, which may be of the kind attached to the garment with which they are worn permanently by sewing, or of the kind attached 5 replaceably by buttons or other fasteners, and to the method of making them.

The prior art as heretofore practised has provided garments of the class referred to intended to be worn in a soft state without 10 laundry starching; garments intended to be starched; and imitation garments of the stiff type, made of a fabric and additions of one sort or another, such as heavy coatings of white pigments and binders of celluloid, 15 rubber and other hard calendered substances, which sometimes have been embossed to take the appearance of the cloth they are supposed to imitate.

None of these types of collar or cuff is 20 really satisfactory. The soft type, consisting of the cloth only, is subject to rumpling, and consequently soiling, after slight use. The soft fabrics also cling to the wrist or the neck of the wearer in an uncomfortable manner, so that, although their vogue 25 is for summer wear, it is the fact that this type of collar or cuff is warmer and less comfortable to wear in summer than the stiff collars upon which it is supposed to be 30 an improvement. With certain informal summer clothing, however, the present sense of appropriate dressing calls for a soft negligee collar and cuff, and there is demand for a more efficient article of this 35 type.

The stiff starched collar, while of good, if of too formal appearance, still remains exceedingly perishable, being subject to wilting under the moisture of perspiration or 40 damp weather, so that one of these collars or cuffs can seldom be worn a whole day with satisfaction. Soft collars, worn without starching, obviously are open to this objection to a less extent than stiff collars, 45 since the normal appearance of the soft collar as heretofore made is rumpled despite the various well-known expedients for maintaining unstarched collars in a decently neat condition.

50 The laundry finishing operations heretofore relied upon comprise starching to a considerable stiffness and flattening in a folded state under ironing heat and pressure.

In the case of stiff collars of the folding 55 type and in less degree with other types,

damage by wear during laundry operations is excessive, the average garment being capable of being worn only a few times before the cleansing operation destroys it.

The imitation-fabric collars and cuffs are 60 not really deceptive, and their use is associated in the public mind with careless personal habits.

It is therefore highly desirable satisfactorily to replace the limp soft collar and 65 cuff and the heavily starched stiff collar and cuff with textile-fabric or genuine articles of this sort which shall be cleanly, of good appearance and not subject to rapid damage in use, and capable of being refreshed in a 70 simpler way than the laundry operations required for a stiff collar.

The present invention provides a way of retaining the shape of a collar or cuff of 75 this general type and preserving its appearance in use until sufficiently soiled to necessitate laundering.

This invention therefore has for its principal object to provide a collar or cuff adapted to resist rumpling, soiling and the 80 effects of moisture or perspiration, and adapted to be cleansed and refreshed by ordinary washing, with or without pressing; to avoid starching; to minimize the laundry wear; and in the case of soft or negligee 85 collars, to provide against the discomfort of limp and clinging fabrics next the skin; and to provide an improved mode of making such garments.

A further object of the invention is to 90 provide a genus of collars and cuffs adapted to be laundered without starching and inherently capable of retaining the desired finish in respect to flatness, folded form, and freedom from rumpling and creasing in 95 use, and which will retain these properties although subjected to heat and moisture and the other casualties of use.

I have elected to illustrate my invention by certain forms only of collars and cuffs, 100 as shown of the fold-over type.

In the drawing,—

Figure 1 is an elevation of a fold-over collar made according to my invention in its flat state;

Figure 2 is a perspective of the outside of the left-hand end of a collar illustrating a modification;

Figures 3, 4 and 5 are respectively typical cross sections of fold-over collars of differ- 110

ent fabric construction each embodying the invention; and

Figure 6 is an elevation of the infolded face of a fold-over cuff made according to 5 the invention.

Referring now to Fig. 1, a separate collar of the fold-over type as therein shown comprises one or more plies 1 of a suitable textile fabric cut and appropriately edge-folded 10 to any desired shape, for example that shown, and sewed at 2 along the margin to provide material for a band portion 3 and a top portion 4, which may be integral, as shown, or separate. The band 3 of which 15 the inside surface appears in Fig. 1, may be provided with any suitable button-holes 5 and, if desired, an attached flat button 6. If the collar is to be a soft collar, I prefer to employ a fabric or fabrics of sufficient body 20 and stiffness, as known in the art, and the whole thickness of the collar may be supplied by one layer of multi-ply fabric, by two layers of such or of single-ply fabric, or by any desired number of separate plies.

25 For instance, in Fig. 5, I have shown in cross-section a collar made of two layers *a* and *b* of which at least one may be a thick heavy canvas, or a piqué, or other two-or-more-ply interwoven linen or cotton cloth, the overlaid blanks being turned in at the edges 7 and stitched at 2. Fig. 3 shows a structure of one layer of thicker and heavier multiply cloth, the edge being bound by a tape 9 and stitched at 10. In Fig. 4 the 30 structure is the same as that of Fig. 5, except that the band 3^b and top 1^b are made separately and sewed together at 11, the top having one ply overlapped on the other at 12, for an edge finish.

40 In either (or any other suitable) construction, the band portion is so treated as to resist soiling, rumpling, and the absorption of moisture, by the application to it of, and impregnation of the interstitial spaces be-

45 tween the fibres of its yarns with, a suitable water-proof cementitious and adhering material characterized by resistance to solution in or very difficult solubility in soapy or alkaline washing liquids, and resistance to 50 change by moderate heat, such as ironing heat. This material may be any material adapted to secure the specified results, but I prefer to employ a plastic, cementitious adhesive solution of cellulose in a solvent.

55 Cellulose acetate dissolved to a limpid consistency in acetone (or other suitable volatile solvent), but having sufficient cellulose acetate in solution to leave a substantial residue upon evaporation of the solvent, 60 is an advantageous and preferred material adapted to remain unchanged through often-repeated washing or ironing, or both. The treating solution may be suitably varied, however, without departing from my invention, by the addition of or substitution of

ingredients, for the purpose of altering the consistency, stiffness, resilience or other qualities of the residue.

In some cases, I may employ other translucent, transparent or white cementitious substances. For example, I may prepare a solution containing about 30% of casein in water by warming and the addition of a small quantity of ammonia, providing a thick paste, which is applied to the collar, allowed 70 to dry partially, and then subjected to the action of a bath containing formaldehyde in about 20% solution. The resulting reaction coagulates the casein application to a waterproof, elastic and stiff consistency adapted 75 to withstand laundry processes.

80 Whatever particular waterproof impregnating agent is chosen, its consistency, quantity and mode of application are such as to reach the effect of waterproofing, smoothing, and sufficiently stiffening the fabric to cause it elastically to resist rumpling, soiling and wetting, and to remain stiff when moist.

85 Preferably the application to the fabric is translucent or transparent, so that the color and texture of the treated fabric is not materially altered, but is displayed beneath and through the applied materials, the application of which sometimes may be increased 90 or repeated, if desired, so as to form a perceptible coating when dry. The object is not to stiffen the cloth to board-like stiffness, or necessarily to fill its textural interstices, but to impregnate and protect the component yarns so as to stiffen them and render the fabric impermeable to moisture except under prolonged agitation and soaking. Fabric so treated may be laundered by usual 95 methods without starching, flat drying and pressing with a comparatively cold iron being sufficient to restore the flatness and good appearance of the treated parts after washing.

100 I have explained and claimed another 105 utilization of the generic type of such applications to fabric garments in my application Serial No. 206,389, filed December 10, 1917 of which this application is a continuation in part.

110 I utilize the waterproofing and stiffening effect of the impregnation for the present purpose by limiting its application in such a way as to determine a place of fold or other edge of the garment. In Fig. 1, for 115 instance, the top edge 15 of the band part of the collar determines the fold *f*, Figs. 3 to 5, and according to my invention, this edge is determined by one boundary of the impregnation, the top 4 being, as shown in Figs. 1 120 and 3 untreated. The fold line, if the collar is desired to have a stiff or semi-stiff top, may be defined on both edges, the top being treated to the line 16, Fig. 5, parallel with the line 15. The same treatment may be 125 130

employed for a cuff 20, Fig. 6, the impregnated areas 21, 21 being separated by an untreated place 22 to determine a more flexible line for folding. In the case of either collar or cuff, when the structure is of more than one ply, the impregnation may, if desired, be confined to one ply only, or less than the whole number. While the impregnation is indicated in the drawings by shading, it will be understood that it is effectively little apparent or wholly invisible, depending upon the degree of treatment, except as a flatter and a stiffer place in the texture of the garment as a whole, and preferably, because of this, extends through the entire thickness of the collar or cuff.

In the case of the cuff 20 and the two-or-more separate-ply types of collars such as shown in Figs. 4 and 5, the impregnating agent may be, and preferably is employed in sufficient consistency and quantity to stick together the separate plies at the impregnated areas. I may employ any desired mode of applying the impregnation conducive to uniformity and accuracy, such as application by a printing block charged with the liquid substance, by brushing, by padding, or by spraying; application through a stencil delimiting the area; application through hollow dies stopping off the remainder of the fabric not intended to be impregnated, in the manner of press-dyeing.

In either case I may prevent inaccuracy in the edges of the impregnated area by treating the adjacent portions of the fabric not intended to be impregnated with a resist. For instance, the fold lines *f* of the collars referred to or the line 22 of the cuff 20 may first be treated by application to them of a water-soluble starch solution of pasty consistency, by printing, stencil or otherwise; dried; and then the impregnating agent may be applied, dried in shape, and the resist removed by washing. After impregnation, the collar or cuff may be dried in form, or pressed in folded form after drying, or both. Before package for sale, I prefer to wash and laundry-iron the treated collars or cuffs, this step effectually removing the odor, if any, of the solvent for the treating substance.

My invention in any of its forms may also include, see Fig. 2, an application of the waterproof cementitious material to portions of the collar or cuff subjected to excessive wear in use, such as the corner of the overhanging top at 25, as shown in Fig. 2, or to the edges of limp areas, for the purpose of aiding these areas to remain flat, or bent in some particular form; for example, the in-turned edge 12 of the top layer 1^b Fig. 4, may be so treated; or any other line or boundary may be so treated.

Collars and cuffs according to my invention are laundered by washing and flat drying, and if desired also by ironing, and in

either case retain indefinitely their flatness, their shape and their resilient stiffness (at the band portion of the collars, for instance) where stiffness is desired.

I claim:

1. A collar or cuff of textile fabric having therein an area impregnated with a waterproof cementitious material and an area in its natural state, the boundary between said areas being at a predetermined place therein. 70

2. A collar or cuff of textile fabric having an area terminating at an edge adapted to constitute a line of fold and rendered stiffer than the remainder of the fabric by impregnation of the fabric of said area with a 80 waterproof cementitious substance.

3. A collar or cuff comprising a homogeneous textile fabric layer having an area terminating at an edge adapted to constitute a line of fold and rendered stiffer than the 85 remainder of the fabric by impregnation of the fabric of said area with a waterproof cementitious substance.

4. A fold-over collar or cuff of textile fabric having therein a delimited area only 90 resulting from uniform impregnation of the fabric with a resilient substance, said area ending at a boundary between impregnated and unimpregnated fabric, said boundary determining the position of the fold in the 95 collar or cuff.

5. A fold-over collar or cuff of textile fabric having therein a delimited area only 100 resulting from uniform impregnation of the fabric with a cellulose residue insoluble in aqueous, soapy or alkaline washing liquids, said area ending at a boundary between impregnated and unimpregnated fabric, said boundary determining the position of the fold in the 105 collar or cuff.

6. A fold-over collar or cuff of textile fabric having a band portion and a top portion, the band portion being stiffened, water-proofed and held smooth by interstitial impregnation of its component yarns with the 110 residue of a locally applied water-proof substance, the portion of the collar or cuff adjacent the impregnated area and constituting the fold line being in its natural unimpregnated state. 115

7. A fold-over collar or cuff of textile fabric having a band portion and a top portion, the band portion being stiffened, water-proofed and held smooth by interstitial impregnation of its component yarns with a 120 residue containing cellulose acetate, the portion of the collar or cuff adjacent the impregnated area and constituting the fold line being in its natural unimpregnated state.

8. A fold-over collar or cuff having a 125 band and a top, the band being stiffened, water-proofed and held in shape by interstitial impregnation with a translucent waterproof cementitious plastic material, the impregnation ending at a predetermined line, 130

and constituting an edge from and over which the top folds.

9. A fold-over collar or cuff having a band of a plurality of plies and a top, the band being stiffened, water-proofed and the plies cemented together and held in shape by interstitial impregnation with a translucent water-proof cementitious plastic material, the impregnation ending at a predetermined line, and constituting an edge from and over which the top folds.

10. A fold-over collar or cuff having an integral band and top of continuous textile fabric, the band being impregnated with a water-proof cementitious material terminating at a line adapted to demark and induce a fold line.

11. The art of making textile fabric collars or cuffs comprising applying to and interstitially impregnating the component yarns of a predetermined area of the fabric only with a cementitious water-proof substance.

12. The art of making textile fabric collars or cuffs comprising applying to and interstitially impregnating the component yarns of a predetermined area of the fabric only with the residuum of a cellulose solution adapted to resist solution in water and alkaline wash liquids, and the action of moderate heat.

13. The art of making textile fabric col-

lars or cuffs comprising applying to and interstitially impregnating the component yarns of a predetermined area of the fabric only with a solution of cellulose acetate in a volatile solvent, and drying the treated fabric in the desired form.

14. The art of making textile fabric collars or cuffs comprising applying to and interstitially impregnating the component yarns of a predetermined area of the fabric only with a solution of cellulose acetate in a volatile solvent, drying the treated fabric in the desired form, and washing and ironing the finished articles.

15. An article of wearing apparel made of separate layers or plies of fabrics secured together by an intermediate layer or layers of binding material, the said layer or layers of binding material being omitted along a narrow zone to form a portion of increased flexibility along which the article is adapted to fold.

16. A folding collar made of separate layers or plies of fabric forming both the neckband and folding portions of the collar, said layers or plies being secured together by an intermediate layer or layers of binding materials except at the fold line of the collar.

Signed by me at Boston, Massachusetts, this 30th day of August, 1921.

FRANCIS W. TULLY.
